Specification of Letters Patent.

Patented Sept. 8, 1914.

Application filed August 14, 1912. Serial No. 715,001.

To all whom it may concern:

Be it known that I, LEWIS GINTER YOUNG, a citizen of the United States, and resident of New York city, New York, have invented certain new and useful Improvements in Flying-Machines, of which the following is a specification containing a full, clear, and exact description, reference being had to the accompanying drawings, forming a part hereof.

This invention relates to flying machines with fixed wings and has for its general object to enable the equilibrium of such a flying machine to be restored automatically whenever it is disturbed. The stability of a flying machine, as is now well understood in the art, depends upon the relation of the centers of pressure—that is, the points at which the pressure resultants act—both upward and downward, upon the wings to the center of gravity of the entire machine and to each other. In a comparative sense longitudinal stability, that is, stability in the general direction of flight, is perhaps more difficult to preserve than is lateral stability and might therefore be regarded as the more important of the two, but as lateral stability has a direct influence upon longitudinal stability it is necessary also to provide means for the preservation, under varying conditions, of lateral stability as well as of the longitudinal stability. Heretofore reliance has been placed, for the preservation of stability in both directions, upon various devices which are controlled by the aeronaut, such as the warping of the wings, movable ailerons, and elevating planes and rudders; but the use of such devices not only involves in some cases, as in the provision for warping of the wings, weakness of structure, but, what is more important, it involves great strains on the working parts under which breakages frequently occur and result seriously. It is well established that a very large percentage of serious accidents are due to this cause.

It is the object of this invention to overcome the weaknesses and difficulties in construction and in operation already referred to and to provide for the automatic recovery of equilibrium of the machine, when it is disturbed, through the action of fixed wings or aerofoils, which are so shaped that when the flying machine is tipped from its normal position in flight, to one side or to the other or forward or backward, a couple shall be

established between the centers of pressure which will tend to restore the machine to its position of equilibrium. Each wing or aerofoil must be considered not only as to the relation which its several parts bear to each other, but also as to the relations which each wing and its centers of pressure bear to the body of the machine, both with respect to the longitudinal axis of the machine, about which it tilts to one side or the other, and the lateral axis of the machine, about which the machine tilts downward or upward in a forward direction, and with respect especially to the center of gravity of the machine. To permit the desired maneuvering of the machine to be effected the body of the machine may be provided with a vertical rudder, for the purpose of turning the machine about a vertical axis, and with horizontal planes, preferably mounted on a flexing tail, for the purpose of directing the flight upward or downward, and the wings themselves may also be provided with deflectors for temporary use in controlling the machine.

In a general sense each wing has a supporting surface adjacent to the body and to the front edge of the wing, with a longitudinally stabilizing surface to the rear of the supporting surface and a laterally stabilizing surface at the side or toward the tip of the wing remote from the body. The supporting surfaces are so curved that the pressure resultants of the two surfaces, whether the flying machine be inclined in one direction or the other, meet at a point in a line above the center of gravity of the machine, and although the distance of the center of pressure of one wing from the longitudinal axis of the machine varies inversely as the distance of the center of pressure of the other wing, the resultant of the upward pressure against the lowermost wing is increased while that against the uppermost wing is decreased, and the machine is therefore returned to a position of equilibrium. Moreover it has been found, in the present instance, that it is desirable to preserve in the structure of the machine a definite relationship; thus, if the main part of each wing, as will be explained hereinafter, has a ratio of length (in a lateral direction from the body) to width (in a longitudinal direction) of two to one, then the distances of the center of pressure of the laterally stabilizing surface and of the center of up-

ward pressure on the under side of the wing from the longitudinal axis should also be in the ratio of two to one, and the distances of the center of pressure of the longitudinally stabilizing surface end of the center of upward pressure on the supporting surface from the lateral axis should also be in the ratio of two to one.

In accordance with the invention each wing or aerofoil has adjacent to the body or longitudinal axis of the machine and its own forward edge a supporting surface, concave below, curved both in a longitudinal direction and in a lateral direction, with a reversely curved longitudinally stabilizing surface to the rear and a reversely curved laterally stabilizing surface at the side remote from the body, the centers of pressure of these surfaces having, as already indicated, substantially the same ratio of distances from the longitudinal axis and from the lateral axis as that which the length of the wing portion has, in a general sense, to its width. The various features of formation of the wing will be described more fully hereinafter with reference to the accompanying drawings in which it is illustrated and in which—

Figure 1 is a top view of a flying machine constructed in accordance with the invention, one of the wings being broken off, while the deflector of the unbroken wing is shown in its extended position. Fig. 2 is a view of the same in side elevation, the wing nearer the eye being shown in section. Fig. 3 is a view of the same in front elevation. Fig. 4 is a detail view in longitudinal section through the flexible tail portion of the machine. Fig. 5 is a detail plan view showing a portion of one of the wings with its deflector which is represented by full lines in its closed position and by dotted lines in its extended position. Fig. 6 is an edge view of the deflector shown in Fig. 5. Fig. 7 is a partial view in section on the plane indicated by the line 7—7 of Fig. 5. Fig. 8 is a partial view in section on the plane indicated by the line 8—8 of Fig. 5. Fig. 9 is a diagrammatic plan view representing the configuration of the nearer or main portion of a wing. Fig. 10 is a diagrammatic view illustrating the wing curvatures from front to rear. Fig. 11 is a diagrammatic plan view of a complete wing, illustrating the curvatures. Fig. 12 is a diagrammatic view illustrating the curvatures of the wing in lateral directions. Fig. 13 is a diagrammatic plan view of the wing, somewhat similar to the view shown in Fig. 11. Figs. 14—60 18 are diagrammatic sectional views taken transversely of the wing and on the planes indicated by the lines 14—18 respectively in Fig. 13. Fig. 19 is a diagrammatic view, looking at the front edge of the wing shown 65 in Fig. 13, and illustrating the curvatures

thereof in lateral directions. Figs. 20 and 21 are diagrammatic sectional views taken on the planes indicated by the lines 20 and 21 respectively of Fig. 13.

The body 1 of the flying machine is made 70 of any suitable shape and material, and is provided internally with a motor and suitable controlling devices not shown and at its forward end with a suitable propeller 2, while its rear portion 3 is flexible, being 75 composed of successive sections which are flexibly connected so that the whole of the tail portion 3 4 can be flexed up or down at the will of the aeronaut, the successive sections being provided with horizontal planes 80 5. Pivotedly mounted at the rear end of the flexible tail portion is a vertical rudder 6 provided with tiller arms 7 to which are connected operating wires 8 which are extended forward within the body. Each 85 wing or aerofoil may be made of any suitable material. By necessity of construction as well as by preference each wing or aerofoil has substantial thickness, as indicated in Figs. 2, 7 and 8, with its greatest thickness 90 near the forward edge and tapering toward the rear, and it may be supported in part by a suitable frame work 9, but each wing will be described hereinafter as though it were a thin sheet of uniform thickness 95 and having sufficient stiffness to enable it to retain its form at all points under all conditions of pressure. It will be understood that the two wings are symmetrical with respect to the longitudinal axis of the machine 100 and a description of one will suffice for the other. In plan outline the wing may be regarded as consisting of two portions, the main or body portion being indicated in Fig. 11 by the points A D A'' D'', while the other 105 or outer portion is indicated in the same figure by the points A'' D'' K.

For convenience in description and clearness in explanation of the definite relationship which characterizes the structure of the 110 wing it may be said that each wing portion (reference being had first to the main or body portion), is laid out on the plan of a base rectangle (although when fitted to the other wing portion appearing as a trapezoid) indicated generally by the straight lines between the points A E A'' E'', the length of which, in the wing shown in the drawings, is nearly twice the width. In this particular construction this approximate 115 ratio of two to one between the length and the width is the ratio which determines the relationship of the distances of the centers of pressure from the longitudinal and lateral axes—that is, the relationship of the distances of the center of sustaining pressure and the center of longitudinally stabilizing pressure from the lateral axis and the relationship of the distances of the center of pressure and the center of laterally stabiliz- 120 125 130

ing pressure from the longitudinal axis of the machine. It will be understood, of course, that this definite relationship is approximate only and is not absolute and it will also be understood that the relationship 5 may be varied; thus, if the ratio of length of the rectangle on which the portions of the wing are laid out as pointed out above, to its width is three to one instead of two to one, then the relationship of the centers of pressure is also three to one. Whether the ratio which establishes the relationship is one or another it is desirable to preserve it throughout the same machine. The relationship of 10 the centers of pressure will be referred to again hereinafter when the location of the centers of pressure has been pointed out. The second or outer portion of the wing is also laid out on the plan of a similar base 15 rectangle and appears when fitted to the first named portion as a trapezoid, but the two trapezoids are not joined on a line which is at right angles to the longer sides. The reason for this will be explained hereinafter, 20 but attention is called to the fact now in order that it may be understood why, in 25 Fig. 11, the line of joining of the two parts of the wing or of the two trapezoids, as the line from A'' to E'', is not at right angles 30 to the longer sides of the rectangles.

Although neither wing part A D A'' D'' or A'' D'' K, conforms in plan outline to the rectangle upon the lines of which it is laid out, and although the actual wing portion A'' D'' K is triangular rather than rectangular in general outline, both wing portions are formed alike, as to curvature both in a longitudinal direction and in a lateral direction (reference being had to the longitudinal axis and to the lateral axis of the machine) and are symmetrical as to curvature with respect to the line of joinder A'' D''.

A vertical line drawn through the center 45 of gravity of the complete machine passes of course through the longitudinal axis of the body. What may be called the lateral axis of each wing also intersects substantially the vertical line drawn through the 50 center of gravity of the machine, and is at right angles to the longitudinal axis of the machine, as indicated by the line O O in Fig. 1, and a short distance back from the front edge of the wing.

55 Before a detailed description of the curvature of the wing is entered upon a brief general description of the wing curvatures may assist in arriving at a clear understanding and for the purposes of this general 60 description, as well as of the more detailed description to follow, each of the base rectangles may be regarded as divided into small rectangles, as indicated in Figs. 9 and 11, there being six of the smaller rectangles in a longitudinal direction and nine

in a lateral direction. In following this general description it will be understood that it is based upon the assumption of a rigid wing without substantial thickness and that a concavity on one side presumes a 70 corresponding convexity on the other side.

The portion of the wing surface bounded by the lines which connect the points A C A'' C'' on Fig. 11 is concave below for the greater part although being reversely 75 curved near the line A'' C'' as will appear later, and is curved both in a longitudinal direction (parallel with the axis of the machine) and in a lateral direction. The amplitude of curvature in a lateral direction 80 with respect to the longitudinal axis of the machine is greater near the front edge of the wing than it is near the rear edge, which is to say that the radii on which the curve is plotted increase in length near the front 85 edge of the wing, so that this portion of the wing forms something like a portion of a funnel with its smaller end to the rear. The curvature in a longitudinal direction (with respect to the axis of the machine) is 90 sharper near the front edge of the wing than it is toward the rear, so that the wing surface, both above and below, runs off at the rear in stream lines. The portion of the wing surface bounded by the lines which 95 connect the points C D C'' D'' is concave above, but with a symmetrical curvature with respect to the part forward of the line C C in a longitudinal direction as well as in a lateral direction and is joined to the 100 portion bounded by the lines which connect the points A C A'' C'' without abrupt change of direction, forming a continuation of the stream line surface of the portion adjacent to the body and the front edge. 105 It will be observed that this portion C D C'' D'' is both to the rear of the portion A C A'' C'' and, in part laterally outside of the same—that is, in outline, reversely disposed with respect to the rear portion in 110 a lateral direction (parallel to the lateral axis of the machine). The portion of the outer wing bounded by the lines which connect the points A'' C'' Q is symmetrical as 115 to its curvature with the corresponding part of the surface A C A'' C'', being concave below. The portion of the outer wing bounded by the lines which connect the points C'' D'' Q K is also symmetrical with the corresponding portion of the surface 120 C D C'' D'' and is concave above, being similarly joined with the surface A'' C'' Q so as to form a continuation of the stream line surface.

When the machine is in a horizontal position, with the wings at a normal angle of incidence, the center of pressure upward on the supporting surface A C A'' C'', that is, the point at which the sum or resultant of all of the upward pressures on the wing 125

may be regarded as applied, is located at about the point marked by the letter H in Fig. 11, in the fourth smaller rectangle from the left of the third series from the 5 front edge of the wing. The center of pressure, upward or downward as the case may be, on the stabilizing portion of the wing surface, when the machine is in a normal, horizontal position, is about at the point 10 indicated by the letter L in Fig. 11, in the eighth smaller rectangle from the left of the fifth series from the front edge of the wing. This stabilizing surface is a longitudinally stabilizing surface or a laterally 15 stabilizing surface or both according to the position of the machine and while the stabilizing centers of pressure—that is, the laterally stabilizing center and the longitudinally stabilizing center—may coincide in 20 the normal position of the machine (as illustrated), under actual conditions of flight they may be more or less widely separated so that it is proper that the wing should be regarded as having a longitudinally stabilizing surface in rear of the sustaining or supporting surface and a laterally stabilizing surface at the side of or outside of the sustaining surface.

It will be observed that the centers of 30 pressure have been located in this description with reference to the normal, horizontal position of the machine. If the wing were a true plane, so that a straight line, in any direction, would lie wholly within the 35 surface, the center of sustaining pressure might shift somewhat with varying positions of the machine, but the resultant of the sustaining pressure would be vertically upward so that, in a machine equipped with 40 plane, rigid wings, there is no such application of force to the wings as to tend automatically to restore the equilibrium of the machine when it has been disturbed; on the contrary, the tendency of the forces applied 45 to the wings of such a machine, when equilibrium is disturbed, is to tip the machine farther in the same direction. In the present machine, however, by reason of the curvature of the wing not only do the centers 50 of sustaining pressure of the two wings—that is, the point at which the sustaining pressures act—shift with varying positions of the machine but the resultants of the sustaining pressure that is, the pressures 55 themselves exerted against the under sides of the two wings are also varied although the resultants still meet in a line drawn vertically through the center of gravity of the machine and above the center of gravity, so 60 that the machine continues in a condition of indifferent stability but with an increased pressure resultant against the lower wing which tends to restore the machine to a position of equilibrium. Of course, as the machine 65 tilts upward on one side the center of

sustaining pressure on that side moves farther from the longitudinal axis of the machine and its leverage increases, although the resultant of the sustaining pressure on that wing still meets the resultant of the 70 sustaining pressure on the other wing in the vertical line drawn through the center of gravity of the machine, and such resultant is relatively reduced.

Although the machine still remains in 75 indifferent stability after its equilibrium has been disturbed, with a tendency to return to a position of equilibrium, as already explained, it is desirable to provide other means to restore the equilibrium. This is 80 accomplished automatically by the stabilizing surfaces. The direction of pressure, upward or downward, on the stabilizing surfaces, or rather the preponderance of pressure upward or downward, depends upon 85 the inclination of the machine. If the machine dips downward from the predetermined angle of normal flight, so that the preponderance of pressure is exerted upon the upper side of the longitudinally stabilizing surface, then the center of pressure L downward will be located in rear of the center of sustaining pressure H and at a distance in rear of the lateral axis, as compared with the distance of the center of sustaining 90 pressure, in the predetermined relationship, that is, in the wing shown, in approximately the ratio of two to one. With its greater leverage of two to one the stabilizing pressure will quickly correct the disturbing factor of pressure and restore the machine to its position of equilibrium. In like manner, if the machine tilts upward too much, the preponderance of pressure on the stabilizing surface will be exerted against the 95 under side of the wing and in the same relationship so that the machine will be returned to its position of equilibrium. It will be understood that by reason of the 100 curvature of the sustaining surface of the wings in a longitudinal direction, the resultants of the sustaining pressures exerted against the two wings continue to meet in a vertical line drawn through the center of gravity of the machine, for all ordinary disturbances of position, whether the machine dips downward or tilts upward in a longitudinal direction.

In like manner when the machine is tilted laterally to one side a pressure is exerted 105 against the upper laterally stabilizing surface of the wing on the upper side in the vicinity of the point L and as the center of such laterally stabilizing surface has a predetermined relation (in this case two 110 to one) in distance from the longitudinal axis of the machine, with respect to the distance of the center of sustaining pressure on the same side, the leverage through which the laterally stabilizing 115

pressure acts is greater than that of the sustaining pressure on the same side and the machine will be thereby restored to its position of equilibrium. The action of the laterally stabilizing pressure against the higher wing; when the machine is tipped laterally, is supplemented by an increase of sustaining pressure on the lower side through the direction of the flow of air, in the manner hereinafter explained, under the lower wing into the region of the sustaining surface adjacent to the body of the machine.

It will be understood, of course, that in the foregoing description the pressures referred to are those which are developed by relative motion of the machine and the air in the flight of the machine through the air. It will also be understood that the pressures which act to restore the lateral equilibrium of the machine, especially that which acts upon the under side of the lower wing, as just explained, tend also to prevent the drifting or slipping of the machine laterally when it is tilted, whereby a frequent cause of accident is removed.

It will be understood that if sustaining and stabilizing surfaces, having in general the relations and functions already described, are provided for the wing, the precise mathematical curvature or type of curvature hereinafter described may be varied more or less, nevertheless it is believed that the most satisfactory results will be attained by the employment of parabolic curves in the formation of the wing surfaces. Thus, the curvature of the wing in a longitudinal direction, from the front edge or line A A'' to the line C C'', and from the line A'' Q to the line C'' Q is a parabola, with the shortest or sharpest curvature at the front, while the curvature from the line C C'' Q to the rear edge of the wing or the line D D'' K is also a parabola, but reversed, being convex below and with its shortest curvature at the rear. It will be noted that the two parabolas for any section of the wing are joined along the line C P C'' P' Q and that they are so joined as to preserve the stream lines and prevent any abrupt change of curvature. It will also be observed that the two sections of each wing, namely the body section or portion and the outer section or portion, are symmetrical as to the curvature in a longitudinal direction, with respect to the lines A'' D'' on which the two sections or portions are joined. All of this is clearly indicated by the double thin lines on Fig. 11. The curvature of the wing in a lateral direction is also parabolic, as represented particularly in Figs. 9 and 10, with a curved surface, concave below, adjacent to the body, followed laterally by a reversely curved surface, concave above. At the front edge of the wing the parabolic curve, concave below, is of the greatest amplitude that is,

plotted on radii of the greatest length, extending from the point A or the longitudinal line I on the front edge of the base rectangle to the line III on the front edge of the base rectangle, and is of least amplitude at the rear, extending, at the rear edge of the base rectangle, from the longitudinal line I to the longitudinal line II, while intermediate parabolas vary in amplitude between these extremes. There is thus formed, as already explained, an under concave surface which is wider at the front and narrower at the rear, forming something like a portion of a funnel, so that there is greater compression of the air, in the flight of the machine, toward the rear edge of the wing and close to the body of the machine, where the greatest sustaining pressure is required.

The parabolic curves of the other part of the inner or body section or portion of the wing are reversed, being concave upwardly, and are also reversed in order as to radius, the radius of the parabolic curve at the front of the wing being least while the amplitude at the rear is greatest.

It will be understood that the two parabolic curves at every point are joined without abrupt change of curvature or direction, so that the stream line surface is preserved laterally as well as longitudinally (with respect to the longitudinal axis of the machine).

The second or outer portion or section of the wing, bounded by the lines A'' D'' K, is symmetrical with the inner or body portion, bounded by the lines A D A'' D'', with respect to the line of joinder of the two parts or sections at A'' D'', so far as concerns the curvature in a longitudinal direction and in a lateral direction.

It will be seen by reference to Fig. 11 that if the wing were extended to the rear line of each base rectangle, there would be at the rear edge of the wing a rather sharply upturned portion which would produce discontinuity of flow, occasion the formation of a partial vacuum along the rear edge of the wing, and create thereby a considerable resistance to the forward motion of the wing. To avoid this undesirable result, the wing is cut off along the line of the low points of the reversed parabolic curves toward the rear edge of each base rectangle, thereby securing a true stream line surface, both at the upper side and at the under side of the wing.

The front edge of the inner or body portion or section of the wing, viewed in plan, is preferably formed on a parabolic curve, as indicated in Fig. 11. If the outer portion or section of the wing were symmetrical in plan with the inner or body portion, there would be a center of sustaining pressure near the outer end and forward edge, symmetrically placed with the center of

pressure H of the inner or body portion. Such a center of pressure, so far remote from the body of the machine, would be undesirable and this portion of the wing is therefore cut off on a line which, for the greater part of its length, is back of the line of high points of the theoretical parabolic curves, as shown in Fig. 11. The wing is thus left, for this portion of its length, with an upwardly directed margin which has some sustaining effect but a more important effect in directing the flow of air, under some conditions, inwardly toward the body of the machine so that it aids in supporting the body when the corresponding wing is lowermost and, as hereinbefore described, assists in preventing the lateral drifting or slipping of the machine when it is inclined laterally.

20 While the general curvatures transversely and longitudinally of the wing and the relationship thereof to the centers of pressure will be understood from the foregoing description, it is believed that reference to Figs. 13—21 in which are illustrated, somewhat diagrammatically, the precise curves employed in the preferred embodiment of the improved wing, will be conducive to a clearer understanding of the form desired.

25 Each of the sections shown in Figs. 14—18 and in Figs. 20 and 21 are taken with respect to the same horizontal line or base plane which has been indicated by dash-dot lines in each of said figures. In this manner, by reference to any one of the transverse sections and the approximate point of intersection thereof by any one of the longitudinal sections, it becomes possible to ascertain substantially the height of the wing above said base horizontal line or plane. By taking another point of intersection of such transverse and longitudinal sectional lines, it becomes possible to locate the height of some other point with respect to the same base line or plane. After locating a sufficient number of these points in such manner the relationship of the points to each other will bring to mind clearly the relationship of the curvatures of the wing considered in any direction. Not only may the character of the curves be thus determined but the extent of the curvature and the high and low points along the transverse and longitudinal parabolic curves may be plotted. Moreover, the relationship of the various curved portions, as such, to other curved portions can be seen. For instance, the funnel like portion on the bottom convex curve of the wing, referred to hereinbefore, is readily located by reference to Figs. 19—21. Fig. 19 shows that the front edge of the wing intersects the base horizontal line at a point relatively remote from the inner edge of the wing. Fig. 20 shows that along the sectional line 20—20, the amplitude of the curvature

of the wing on its underside becomes less and the sectional line 20—20 accordingly intersects the horizontal base line at a point nearer to the inner edge of the wing. Likewise, the sectional line 21—21 intersects the horizontal base line at a point very near to the inner edge of the wing, the relationship of these various points of intersection indicating clearly that a funnel like portion is formed on the bottom convex surface of the wing.

Under some conditions, particularly in the execution of some maneuvers, it may be desirable to direct toward the body of the machine, under the wing, so that a greater sustaining effect may be produced, a greater volume of air than would be directed or deflected by the outer portion of the wing when cut off along the line A'' Q K, as already described. Accordingly there is provided for each wing a deflector 10 which is movably secured to the outer portion of the wing at its forward edge and is conformed thereto so that when it is not extended it lies close against the wing. It is connected to the wing by a pivotal connection 11 which permits it to be extended forwardly and rotated to move its front edge downwardly. At its outer extremity it is connected to a curved rod 14 which slides freely in guides 12 and 13 secured to the wing. Between its ends, on its under side, near the forward edge, is secured a stud 15 which is engaged by a slotted arm 17 on a vertical rock shaft 16. The latter is mounted in a suitable bearing secured to the wing and is provided with arms 18 which are connected by operating wires 19 with an operating lever 20 mounted in the body of the machine. By extending either deflector a greater volume of air may be directed under the corresponding wing toward the sustaining surface of the wing to cause the machine to be tilted upwardly on the corresponding side. It will be understood, of course, that the direction of flight upwardly or downwardly and to one side or the other is controlled through the operation of the flexible tail and rudder, which are essential to the practical use of the machine.

I claim as my invention:

1. A wing for a flying machine having a definite proportion of length and width and having adjacent to the body of the flying machine and to its own front edge a sustaining surface, concave below, curved in a longitudinal direction and in a lateral direction, with a longitudinally stabilizing surface at the rear, the distances of the centers of pressure of the stabilizing surface and the sustaining surface from the lateral axis of the wing having substantially the same proportion as the length and width of the wing.
2. A wing for a flying machine having a

- definite proportion of length and width and having adjacent to the body of the flying machine and to its own front edge a sustaining surface, concave below, curved in a longitudinal direction and in a lateral direction and a laterally stabilizing surface at the side of the wing remote from the body of the machine, the distances of the centers of pressure of the laterally stabilizing surface and the sustaining surface from the longitudinal axis of the machine having substantially the same proportion as the length and width of the wing.
3. A wing for a flying machine composed of two parts, one part having adjacent to the body of the flying machine and to its own front edge a sustaining surface, concave below, curved in a longitudinal direction and in a lateral direction, and having also a reversely curved laterally stabilizing surface at the side remote from the body, and a second part curved similarly to the first part and symmetrical with the first part with respect to the line of joinder of the two parts, the two parts being joined along substantially the line of the low points of the reverse curves without abrupt change of surface lines.
4. A wing for a flying machine composed of two parts; one part adjacent to the body of the flying machine and to its own front edge, a sustaining surface, concave below, curved in a longitudinal direction and in a lateral direction, and having also a reversely curved laterally stabilizing surface at the side remote from the body, and a second part curved similarly to the first part and symmetrical with the first part with respect to the line of joinder of the two parts, the two parts being joined along substantially the line of the low points of the reverse curves without abrupt change of surface lines, the second part terminating along the curved line extending from the front edge near the point of joining of the two parts to the rear outer portion of the second part, substantially along the line of the high points of the second part.
5. A wing for a flying machine having adjacent to the body of the flying machine and to its own front edge a sustaining surface, concave below, curved in a longitudinal direction and in a lateral direction and a laterally stabilizing surface at the side of the wing remote from the body of the machine, the distances of the centers of pressure of the laterally stabilizing surface and the sustaining surface from the longitudinal axis of the machine having substantially the same proportion as the length and width of the wing.
6. A wing for a flying machine composed of two parts, one part having adjacent to the body of the flying machine and to its own front edge a sustaining surface, concave below, with a reversely curved outer portion, and the other part curved similarly but oppositely placed in a lateral direction and joined to the first part without abrupt change of curvature, the two parts being substantially symmetrical as to curvature on opposite sides of the line of junction of the two parts.
7. In a flying machine, a wing or supporting member provided with an under surface concave and convex, the concave surface terminating at the front edge of the wing in an arched outline and terminating at the rear edge in the arched outline, the amplitude of the arch at the front edge being greater than that of the arch at the rear edge forming a partial funnel with its mouth at the front of the wing and tapering toward the rear and with an upper surface convex and concave, the amplitude of the curvature of the upper concave surface being less at its forward portion than at its rear portion.
8. A wing or supporting member for a flying machine having two distinct areas of determined relationship to each other, one of said areas being a sustaining surface and the other a stabilizing surface, the sustaining area being close to the body of the machine and acting on the air to tend to compress the same and the stabilizing area lying outside of the compression area and composed of two substantially equal surfaces symmetrical with respect to a line of joinder substantially at right angles to the lateral axis of the wing.

In testimony whereof, I have signed my name to this specification, in presence of two subscribing witnesses.

LEWIS GINTER YOUNG.
